[57] CLAIM

The ornamental design for toaster end panels, as shown and described.

DESCRIPTION

FIG. 1 is a perspective view as seen from the top, front, and left side of toaster end panels showing our new design;
FIG. 2 is a left side elevational view thereof;
FIG. 3 is a right side elevational view thereof;
FIG. 4 is a front elevational view thereof;
FIG. 5 is a rear elevational view thereof;
FIG. 6 is a top plan view thereof; and,
FIG. 7 is a bottom plan view thereof.

The broken lines in FIGS. 1 through 7 showing the power cord and toaster body are used for illustrative purposes only and form no part of the claimed design.
